Attest.

UNITED STATES PATENT OFFICE.

JOHN B. GATS, OF CHICAGO, ILLINOIS, ASSIGNOR TO AARON M. SEALES, OF CHICAGO, ILLINOIS.

VALVE.

Application filed December 20, 1922. Serial No. 607,955.

To all whom it may concern:

Be it known that I, JOHN B. GATS, a citizen of the United States, residing at Chicago, in the county of Cook and State of Illinois, have invented certain new and useful Improvements in Valves, of which the following is a specification.

This invention relates to improvements in valves.

10 One of the objects of the invention is to provide an improved valve of the poppet valve type.

Another object is to provide a laminated valve having more or less resiliency and arranged to be seated upon an approximately flat, but slightly curved, surface.

20 Another object is to provide a valve having a seating surface made of a metal to which free carbon will not adhere.

Another object is to provide a valve structure in which there is a slight radial movement of the valve on its seat, whereby to produce a rubbing friction contact to clean the valve and seat surfaces.

25 Another object is to provide an improved manner of connecting a plurality of valve parts to its stem.

Other objects and advantages will clearly appear from a consideration of the following description taken in conjunction with the accompanying drawing, forming a part hereof, wherein:—

Fig. 1 is a central section through the valve and its seat.

35 Figs. 2, 3 and 4 are elevations of the valve stem showing it in different stages of its development.

Fig. 5 is a top plan view of the valve structure before the stem is secured thereto.

40 In all the views the same reference characters are employed to indicate corresponding parts.

The valve 10 consists of a plurality of parallel disks 11—12, perforated as shown in Figs. 1 and 5, at 13, with laterally extending notches 14—14'.

45 The valve stem 15 is formed of a rod 16 upset near one end at 17, then turned down to form a tenon 18 and a shoulder 19. After this has been done, laterally extending wings 20—20' are formed in the tenon to enter the notches 14—14' to prevent the valve for turning on its stem. The end 18 is now expanded, as shown at 21 in Fig. 1 to hold the

disks on the stem. This may be done by 55 heat and pressure.

After the disks 11—12 have been fastened on the stem 15 another disk 22 is forced over the stem 15 and turned over the edges of the disks 11 and 12 at their edges, as at 60 23. This disk also overlies the enlargement 17 by a part 24 enclosing it.

The disk 24 is, preferably, Monel metal which, I have discovered, has no affinity whatever for the free carbon resulting from 65 explosions of the charges of internal combustion engines. In other words, free carbon will not adhere to the seating surface of a valve which is made of Monel metal. It may also be advantageous to have the valve 70 seat faced with this metal.

The seat 25, upon which the valve 10 is seated, is curved as shown, on slightly longer radii than the curve of the dished valve 10, when the latter is not seated, as shown 75 in full lines and broken lines, respectively, in Fig. 1. When the valve is seated, the curvature of the valve and of the seat is substantially the same.

The valve 10 is made up of dished disks 80 with the stem extending from the concave side.

Pressure from within a cylinder tends to straighten the valve and make it conform more intimately with the surface of the 85 valve seat. Of course, in operations of this character we are dealing with exceedingly small measurements and the relative dimensions and relations shown by the drawing are necessarily exaggerated to be apparent. 90

Another advantage, of a more or less yielding valve body, is the quietude of its operation, and the absence of injury due to impact of the seating surfaces. These 95 advantages are attained by the conical formation of the valve together with its lack of rigidity.

While I have herein shown a single embodiment of my invention for the purpose of clear disclosure, it will be manifest to persons skilled in the art, that many changes may be made in the general arrangement and configuration of the parts, within the scope of the following claims.

Having described my invention, what I 100 claim as new and desire to secure by Letters Patent, is:—

1. A valve structure comprising a valve

having a plurality of dished disks; a stem extending from the concave side of the valve and a valve seat curved on longer radii than the valve in its open position to receive 5 the circumferential concave edge of the valve.

2. A valve structure comprising a valve, dished to provide a concave seating surface and a valve seat beginning at the edge of a 10 bore and extending outwardly therefrom in

all directions on a curve drawn about longer radii than the curve of the valve when not seated.

3. A valve structure comprising a yielding valve having a concave seating surface 15 and a convex valve seat of a different curve.

In testimony whereof I hereunto subscribe my name.

JOHN B. GATS.
